(57) **CLAIM**

The ornamental design for an fully adjustable air deflector system for snow plow blades, as substantially shown and described.

DESCRIPTION

FIG. 1 is a side perspective view of a first embodiment of the fully adjustable air deflector system for snow plow blades of the present invention;

FIG. 2 is a left side view thereof;

FIG. 3 is a right side view thereof;

FIG. 4 is a top view thereof;

FIG. 5 is a bottom view thereof;

FIG. 6 is a rear view thereof;

FIG. 7 is a front view thereof;

FIG. 8 is a side perspective view of a second embodiment of the fully adjustable air deflector system for snow plow blades of the present invention;

FIG. 9 is a left side view thereof;

FIG. 10 is a right side view thereof;

FIG. 11 is a top view thereof;

FIG. 12 is a bottom view thereof;

FIG. 13 is a rear view thereof; and,

FIG. 14 is a front view thereof.

The broken lines shown represent environmental subject matter and form no part of the claimed design.

1 Claim, 10 Drawing Sheets
